SCRAPER FOR A VESSEL CLEANING MACHINE

Harry Cunliffe, Leasowe, Wirral, England, assignor to
The Moreton Engineering Company Limited, Wirral,
England, a British company

Application January 31, 1957, Serial No. 44,691

Term of patent 14 years

(Cl. D9—6)

Fig. 1 is a plan view of a scraper for a vessel cleaning machine embodying my new design.

Fig. 2 is an inverted plan view of the scraper illustrated in Fig. 1.

Fig. 3 is an elevation of Fig. 2 in the direction of arrow III.

Fig. 4 is an elevation, in the direction of arrow IV of Fig. 2, and

Fig. 5 is a rear end elevation of Fig. 2 in the direction of arrow V.

I claim:

The ornamental design for a scraper for a vessel cleaning machine, substantially as shown.
